UNITED STATES PATENT OFFICE.

CHARLES H. DESAULES, OF SPRINGFIELD, MASSACHUSETTS, ASSIGNOR TO THE FISK RUBBER COMPANY, OF CHICOPEE FALLS, MASSACHUSETTS, A CORPORATION OF MASSACHUSETTS.

MANIFOLD COUPLING.

Application filed September 29, 1922. Serial No. 591,374.

To all whom it may concern:

Be it known that I, CHARLES H. DESAULES, a citizen of the United States of America, residing at Springfield, in the county of Hampden and State of Massachusetts, have invented certain new and useful Improvements in a Manifold Coupling, of which the following is a specification.

My invention relates to manifold couplings adapted for use particularly in heaters in which cord tires are vulcanized. In one method of vulcanizing cord tires they are enclosed in molds, a stack of which is assembled in a heater, and held together by means of a hydraulic ram which forces the stack against the cover of the heater. To expand the tires outwardly into the molds they are connected to a source of hydraulic or pneumatic pressure. As a stack may contain in the neighborhood of twenty molds, the pipe by which this pressure is supplied to the tires is very long and is conveniently made sectional. The speed with which a heater can be loaded and unloaded is of great importance in actual operation, and the rapidity with which the sections of the pressure supplying pipe can be assembled and taken apart is a large factor in determining this speed. It is the object of my invention to improve upon existing devices from standpoints of speed of assembly and disassembly, reliability, ease in operation, protection of vulnerable parts against injury, and in various other particulars which will appear from the following description and claims.

The invention will now be described with reference to the accompanying drawings, in which—

40 Fig. 1 is a vertical section of a vulcanizing heater, showing a stack of molds in position for vulcanizing, the heater being shown as broken away to save space;

45 Fig. 2 is a detail, partly in median section, of one section of the pressure manifold shown as attached to fragments of adjacent manifolds;

Fig. 3 is a section on line 3—3 of Fig. 2; and

50 Fig. 4 is a section on line 4—4 of Fig. 2. Referring to Fig. 1, 10 represents the shell of a heater of any usual or desired construction, and having top and bottom members 11 and 12 to which the shell is attached. Through the bottom member 12 passes a hy-

draulic ram 13 carrying a platform 14 upon which the stack of molds 15 rest. By raising the ram the stack of molds may be pressed against the cover 16 of the heater, which is held in place by being rotated so that lugs 17 thereon will lie under lugs 18 on the top member 11. A spacing ring 50 having a slot 51 at one side is preferably located between the top mold and the cover to afford space for certain piping to be described. By this means the individual molds, which are shown as of the usual type split circumferentially into halves, are held closed. Inside the tire 19 in each mold is an annular expandible bag 20 which, when fluid pressure is introduced into it, will force the tire outwardly against the mold. Pressure is supplied to the bags by so-called "pigtails" or flexible tubes 21, extending between the stem of the bag and sections 22 of a vertical pressure manifold. Each pigtail may have a bend 23 in it so that it will be more flexible. The lower section 22 conveniently rests on a base 24 on the platform 14, and the top is connected by a pipe 25 (conveniently bent into a spiral for flexibility) through which air or water under pressure may be admitted. Pipe 25 passes through slot 51 in ring 50 and through the heater wall, and is preferably made separable by a union 52 permitting the pipe to be removed from the inside of the heater during stacking or unstacking of the molds.

As indicated in Fig. 2, and as a preferred construction, each section of the vertical manifold has two pigtails connected to it, these pigtails being permanently located on the manifold section and being connected to the air bags by wing-nuts 26. Each section (except those at the top and bottom) carries at its lower end the top piece of a coupling adapted to connect it to the next lower section, and at its top the bottom piece of a similar coupling adapted to connect it to the next higher section. The top piece of each coupling comprises a nipple 27 having at its bottom an integral nut 28 whereby it may be attached to the pipe section 22, and at its top a seat 29, preferably of spherical or conical form. The upper portion of the nipple 27 is threaded, and a sleeve 30 is adjustably screwed thereon. Surrounding both nipple 27 and sleeve 30 is a protecting cylinder 31, having holes therein registering with threaded holes in the sleeve into which

set screws 32 fit. The cylinder is preferably internally shouldered to interfit with a shoulder 33 on the sleeve, so that the parts will normally fall in their proper positions, 5 and strain on the set screw will be relieved, and is preferably high enough to guard seat 29 from injury when the coupling is being operated or the parts are being separately handled. The inner ends of the set screws 10 fit between lugs 34 on the nipple 27, whereby the nipple and the sleeve will be held in proper adjusted position. Preferably the cylinder 31 has one or more small holes 35 at about the level of shoulder 33 so that any 15 condensed water (the coupling when in use being normally surrounded with an atmosphere of steam) will drain off. The cylinder also serves to protect against injury the threads to be described on the outer surface 20 of sleeve 30.

Threaded to the bottom of each pipe section 22, and forming the top part of each coupling, is a thimble 36 having a spherical or conical seat 37 at its bottom adapted to interfit with the seat 29, and when pressed together by the mechanism to be described to form a steam tight passage 53 between the two adjacent pipe sections. Thimble 36 has a shoulder 38 adapted to support a clamping 30 member comprising handles 39 and a depending sleeve-like portion 40 adapted to fit between the sleeve 30 and the protecting cylinder 31, as shown in Fig. 2. To retain this member in position the thimble is provided 35 with an annular groove into which a spring ring 41 is adapted to fit. When the ring is sprung into position the clamping member is secured in place on the thimble, although free to rotate about it.

40 The outside of sleeve 30 is provided with interrupted screw threads meshing with similar interrupted screw threads 42 on the portion 40, so as to form a coupling of the breech-block type by which, on rotation of the handles 39, the thimble will be drawn 45 tightly against the seat 29, and yet by which two adjacent pipe sections can be separated by giving only a quarter-turn to the handle. The threads are preferably constructed so 50 that the threads on diametrically opposite sides are in similar longitudinal positions instead of being spaced axially from each other by half the pitch of the screw as in the usual screw thread. This is desirable for 55 the following reasons. As shown in Fig. 3, the threads are formed substantially in two opposed quadrants. It is possible to assemble the sleeve 40 with sleeve 30 in either of two positions, 180° apart from each other. 60 Now if the threads were of the usual type one of these positions would bring seat 37 at a different spacing from seat 29 than the other, a condition which would prevent a tight joint being made in one or the other 65 position. By the construction described this

difficulty is avoided, and the parts can be assembled in either position with identical results.

The operation of the device is as follows. Assuming the heater to be empty, two molds 70 are placed on the platform 14 with the air bag valve stems in substantial vertical alignment, the lowest section 22 put in place, and the pigtails 21 joined to the valve stems of their respective air bags by tightening the 75 wing-nuts 26. Two more molds are then placed on top of the pile, and another pipe section placed upon the one previously in place, the sleeve portion 40 on the new section being dropped into the space between 80 sleeve 30 and protecting cylinder 31, with the threads on one member in the interrupted spaces in the other. With sleeve 30 properly adjusted on nipple 27 the threads 85 will be in a condition to mesh when the 90 seats 29 and 37 come together. Preferably, however, the handle 39 is not rotated to tighten the coupling until the wing-nuts 26 holding the pigtails to the air bags are tightened, as the latter operation may require some rotation of the upper pipe section 22 to bring the pigtails into proper registrations with the valve stems. It will be seen from Fig. 2 that until the handle 39 is rotated to actually clamp the two parts of 95 the coupling together, the upper pipe section can be rotated with respect to the lower section, by reason of the type of connection between thimble 36 and the part 39-40. When the pigtails have been set in their 100 proper positions, however, a slight turn of the handle will clamp them and the pipe section firmly in place, and will seal the joint between thimble 36 and nipple 27. The addition of further sections is carried 105 on in the same manner, and finally pipe 25 is attached to the uppermost section. Removal of the molds is accomplished by a reversal of the actions described.

Having thus described my invention I 110 claim:

1. A coupling adapted for use in a cord tire vulcanizer which comprises a coupling member having a bearing seat, interrupted threads secured to said member, a protecting cylinder surrounding the threads and affording an annular space around the threads for the introduction of a clamping member, a second coupling member adapted to seat against the first clamping member and form therewith a fluid tight passage, a clamping member secured to the second named coupling member but free to rotate thereon, unless clamped, said clamping member being provided on its inner surface with interrupted screw threads adapted to mesh with the threads on the coupling member, said threads being similar in the spaces between interruptions whereby the 120 clamping member will operate equally in 125

any position of assembly, and a handle attached to the clamping member for rotating it.

2. A coupling adapted for use in a cord tire vulcanizer which comprises a coupling member having a bearing seat, interrupted threads secured to said member, a protecting cylinder surrounding the threads and affording an annular space around the threads for the introduction of a clamping member, a second coupling member adapted to seat against the first clamping member and form therewith a fluid tight passage, and a clamping member secured to the second named coupling member but free to rotate thereon, unless clamped, said clamping member being provided on its inner surface with interrupted screw threads adapted to mesh with the threads on the coupling member.

10 10 threads for the introduction of a clamping member, a second coupling member adapted to seat against the first clamping member and form therewith a fluid tight passage, and a clamping member secured to the second named coupling member but free to rotate thereon, unless clamped, said clamping member being provided on its inner surface with interrupted screw threads adapted to mesh with the threads on the coupling member.

15 20 25 30 3. A coupling adapted for use in a cord tire vulcanizer which comprises a coupling member having a bearing seat, interrupted threads secured to said member, a protecting cylinder surrounding the threads and affording an annular space around the threads for the introduction of a clamping member, a second coupling member adapted

to seat against the first clamping member and form therewith a fluid tight passage, and a clamping member secured to the second named coupling member but free to rotate thereon, unless clamped, said clamping member being provided on its inner surface with interrupted screw threads adapted to mesh with the threads on the coupling member.

35 40 45 50 55 60 65 4. A coupling adapted for use in a cord tire vulcanizer which comprises a coupling member having a bearing seat, interrupted screw threads secured to such member, a protecting cylinder surrounding the coupling member and the screw threads and affording an annular space around the screw threads, a second coupling member adapted to seat against the first clamping member and form therewith a fluid tight passage, and a clamping member surrounding and protecting the second named coupling member, said clamping member being fixed to such coupling member but free to rotate thereon, and adapted to fit into the annular space within the protecting cylinder, and interrupted screw threads on the inner periphery of the clamping member adapted to slide past the interrupted threads associated with the first named coupling member and to engage therewith upon rotation.
